UNITED STATES PATENT OFFICE

119,203

DESIGN FOR A LIGHT REFLECTING UNIT

Arthur W. Krueger, Chicago, Ill., assignor to
Stephen Zidek, Riverside, Ill.

Application December 17, 1938, Serial No. 81,844

Term of patent 3½ years

To all whom it may concern:

Be it known that I, Arthur W. Krueger, a citizen of the United States, residing at Chicago, in the county of Cook and State of Illinois, have invented a new, original, and ornamental Design for a Light Reflecting Unit, of which the following is a specification, reference being had to the accompanying drawing, forming part thereof, in which:

Figure 1 is a side elevation of a light reflecting unit showing my new design; and

Figure 2 is a bottom view thereof.

The characteristic features of my design are substantially as shown in solid lines in the drawing.

I claim:

The ornamental design for a light reflecting unit, substantially as shown and described.

ARTHUR W. KRUEGER.
